UNITED STATES PATENT OFFICE.

ALLEN D. LINN, OF RACINE, WISCONSIN, ASSIGNOR TO THOMAS KANE, OF CHICAGO, ILLINOIS, AND THE RACINE HARDWARE MANUFACTURING COMPANY, OF RACINE, WISCONSIN.

MEANS FOR AUTOMATICALLY REGULATING THE FLOW OF LIQUID FUEL TO INJECTOR-BURNERS FOR STEAM-BOILERS.

SPECIFICATION forming part of Letters Patent No. 398,418, dated February 26, 1889.

Application filed June 11, 1886. Serial No. 204,845. (No model.)

To all whom it may concern:

Be it known that I, ALLEN D. LINN, of Racine, in the county of Racine and State of Wisconsin, have invented certain Improvements in Means for Automatically Regulating the Flow of Liquid Fuel to Injector-Burners for Steam-Boilers, of which the following is a specification.

This invention relates to an apparatus in which a steam-jet is employed to atomize a hydrocarbon oil and deliver the same, mingled with atmospheric air, either directly into the fire-box or into a retort, from which it is delivered into the fire-box of a steam-boiler.

The aim of my invention is to maintain a uniform steam-pressure by so applying the pressure of the steam that it will properly control the supply of fuel.

To this end the invention consists, essentially, in combining with a steam oil-atomizing jet, in which the steam induces the flow of oil, a steam-actuated diaphragm and two valves connected thereto—one in the steam-supply pipe and the other in the oil-supply pipe—so that an increasing steam-pressure acts with double effect to lessen the rate of oil-delivery—first, by closing the oil-valve, and thus positively checking the flow of oil, and, second, by closing the steam-valve, and thus diminishing the force and volume of the steam-jet, so that its capacity to feed the oil is lessened.

In the accompanying drawings, Figure 1 represents a top plan view of the device. Fig. 2 is a horizontal section through the center of the same on the line *x* *x* of Figs. 2 and 4. Fig. 3 is a transverse vertical section of the same on the line *y* *y* of Figs. 1 and 4. Fig. 4 is a transverse section on the line *z* *z* of Figs. 1 and 2. Fig. 5 is a view in the nature of a diagram illustrating the connection of the device with the steam-boiler and with the retort-burner thereunder.

Referring to the drawings, A represents the frame of the apparatus, commonly cast complete in one piece.

B represents a steam-receiving chamber provided on one side with an inlet-neck, *a*, through which steam is constantly delivered

by a pipe leading to the steam-space of the boiler. The chamber B consists of a cup-like body having a tubular delivery-neck, *b*, screwed into the frame A, as shown in Figs. 2 and 3. The top of the cap B is closed by a flexible diaphragm, *c*, of sheet metal or other equivalent material, adapted to yield under the internal pressure of the steam. To this diaphragm is attached a central hub, *d*, which receives and carries the threaded end of a valve-spindle, *e*. This spindle extends downward through the tubular neck of the chamber, and is provided with an enlarged head or valve on its lower end, so that as the diaphragm is raised by the pressure of the steam this head will close the passage through the neck to a greater or less extent, and thus control the delivery of steam from the chamber *b*. The delivery-neck *b* communicates with a steam-passage, *f*, by which the steam is conducted to a tubular nozzle or spindle, *g*, through which it is discharged into an outlet-pipe, C.

The nozzle *g* is tapered externally at its delivery end and seated loosely within a conical opening or mouth, *h*, in the frame; the construction being such that an annular space exists around the mouth of the nozzle. This space communicates with an oil-passage, *i*, leading through the frame, as shown, and communicating with an oil-supply pipe, D. The steam issuing from the nozzle induces a constant inward flow of oil, which, passing around the exterior of the nozzle *h*, meets the steam issuing from its end, the result being that the oil is atomized, partially vaporized, and in combination with the steam delivered forcibly through the pipe C.

In advance of the nozzle *g* and of the point at which the oil is brought in contact with the steam I provide one or more air-inlets, *k*, through which atmospheric air is constantly drawn and caused to combine with the steam and oil.

In order to resist the steam-pressure upon the diaphragm, I employ a vertical spindle, *l*, bearing at its lower end upon the center of the diaphragm and passing at its upper end through a stuffing-box in the main frame into

the oil-passage *i*. Around this spindle I mount a spiral spring, *n*, bearing at its upper end against a stationary collar and at its lower end upon a collar, *o*, threaded on the spindle that it may be adjusted to vary the tension of the spring.

When the pressure of the steam becomes so great as to overcome the resistance of the spring and move the diaphragm, it has the two-fold effect of closing the valve *e*, so as to diminish the supply of steam to the injector-nozzle, and also by raising the spindle *l* and causing the latter to diminish the flow of oil through the pipe *i*, the oil-delivery and steam-delivery being both diminished automatically through the action of the steam upon the diaphragm.

In order that the delivery of oil and steam may be regulated each independently of the other, I mount in one end of the frame a threaded spindle or valve, *p*, which enters the oil-passage directly opposite the spindle *l*, to control the oil-delivery and thread the spindle *e* into the center of the diaphragm, as shown, so that it may be adjusted in relation to the diaphragm to regulate the steam-delivery. I also mount in the main frame cocks *q* and *r*, by which the oil and steam passages may be completely or partially closed at will. The parts above described may be constructed and united in any appropriate manner; but in order to cheapen and facilitate the construction and to admit of the interior of the apparatus being readily inspected and freed from obstructions, if necessary, I prefer to adopt the details of construction represented in the drawings, and which I will now describe.

The main frame *A* is cast complete in one piece. The oil-passage *i* is formed by drilling two holes at right angles to each other entirely through the frame from side to side and then closing the ends of these openings by screws *s*, as shown in the several figures. By removing these screws the passages are opened, so that a wire or other cleansing-instrument may be passed completely through them. The nozzle *g* is threaded externally at one end and screwed into a threaded hole in the body. This construction admits of the nozzle being adjusted longitudinally in order to vary the size of the annular space around its mouth, as the character of the fuel or other circumstances may render necessary.

The spindles *l* and *p* are mounted in a single tubular guide, *t*, which is drilled longitudinally and centrally and inserted through the frame, as shown, its inner end being provided with a gland, *u*, which serves to retain the packing around the spindle and also as a collar or bearing to support one end of the spring *n*. In line with the nozzle I propose to apply a blow-off cock, *w*, which may, however, be omitted.

The combined oil, steam, and air issuing through the pipe *C* in the form of a misty vapor may be delivered directly into the fire-

box of the boiler for combustion; but it is preferred to extend the pipe *C* into the fire-box in the form of a coil, its inner end being capped or otherwise closed and provided with a series of fine perforations for the delivery of the vapor. The vapor issuing from these openings is ignited, and serves the double purpose of heating the boiler and of maintaining the coil or retort in a highly-heated condition, the effect of which is to completely vaporize the materials passing therethrough, and to raise them to a very high temperature, so that they are delivered at the point of ignition in the best possible condition to insure a perfect combustion.

It is to be particularly noted that in my apparatus the feeding of the oil is effected directly by and is dependent upon the steam-jet, so that variations in the force or volume of the jet are followed by corresponding variations in the rate of oil-delivery. It is further to be noted that the steam-pressure is applied not only to vary the steam-jet, that it may operate as above mentioned, but also to positively vary the size of the oil-passage. It will be perceived, therefore, that the rate of oil-delivery is in my apparatus dependent, first, upon the pressure and consequent velocity of the steam; second, upon the variation of the jet due to the action of the steam-controlling valve, and, third, to the variation in the oil-flow dependent upon the separate oil-controlling valves.

I am aware that a steam-actuated diaphragm has been used to control the action of a steam-oil-atomizing jet, the regulation of the oil-flow being wholly dependent upon variations in the steam-jet. I am also aware that a diaphragm urged in one direction by steam and in the opposite direction by a spring has been connected with cocks controlling the delivery of air and of oil to a furnace, the air-pressure being maintained by external independent means, and the fuel-delivery being effected otherwise than by a steam-jet. I am also aware that a steam-actuated diaphragm has been employed to control the delivery of gas from an external source to a boiler-furnace, and to such combinations I lay no claim.

I believe myself to be the first to apply the steam-pressure of a boiler to regulate an oil-controlling valve and also to regulate a steam-jet by which the oil is directly fed.

Having thus described my invention, what I claim is—

1. The combination of the steam-boiler, the oil-supply pipe, its nozzle for delivering oil to the fire-box, the second nozzle arranged concentric with the first and connected by a pipe with the steam-space of the boiler, so that the steam is caused to effect the delivery of the oil to the fire-box, the valve in the steam-passage, the valve in the oil-passage, and the diaphragm connected with both valves and communicating with the steam-space of the boiler, whereby variations in the steam-pressure are

caused to positively vary the flow of oil by the oil-controlling valve, and further vary the flow by regulating the steam-jet.

2. In an oil-burning boiler, and in combination with the steam oil-atomizing jet, two valves, one in the steam-passage and the other in the oil-passage, and the steam-actuated diaphragm connected with and operating both valves, whereby the oil-passage and the steam-passage are both diminished by increase in the steam-pressure, so that the delivery of oil is positively limited to correspond with the diminution of the steam-jet.

3. In combination with the frame or body having the distinct steam and oil passages therethrough, the intermediate steam-chamber B, with a flexible wall or diaphragm, the internal valve, e, attached to the diaphragm and controlling the flow of steam through the steam-passage, and the spindle l, seated at one end against the diaphragm and acting at its opposite end as a valve to control the flow through the oil-passage.

4. In an apparatus for automatically feeding liquid fuel to a boiler, and in combination with the boiler, an oil-supply pipe, and a delivery-nozzle attached thereto, a concentric nozzle, and a steam-conductor leading thence to the steam-space of the boiler, so that the steam-jet is applied to feed the oil, a steam-actuated diaphragm, two valves connected to and operated by the diaphragm and located

one in the oil and the other in the steam-passage, and two independent valves, q r, for arbitrarily controlling the oil and steam delivery. 35

5. In combination with the oil pipe or passage i, the valve-spindle l, and the diaphragm connected therewith, the independently-adjustable spindle p, arranged in opposition to the first-named spindle, as described and 40 shown.

6. In an oil-burning boiler, the combination of a steam oil-atomizing jet, a valve controlling the oil-delivery therethrough, a second valve controlling the steam-delivery therethrough, 45 and valve-operating devices, substantially as shown, connecting with the boiler and subject to the steam-pressure therefrom, whereby an increase in pressure is caused to diminish the oil-supply and also to diminish the flow of the 50 steam acting to propel the oil.

7. In combination with a frame or body having the passage i therethrough, the tubular body t, inserted through the body and provided with the two valve-spindles entering 55 from opposite sides.

In testimony whereof I hereunto set my hand, this 7th day of June, 1886, in the presence of two attesting witnesses.

ALLEN D. LINN.
